UNITED STATES PATENT OFFICE.

ADOLF A. SWANSON, OF EVERETT, MASSACHUSETTS.

STAIR STRUCTURE

1,420,294.

Specification of Letters Patent. Patented June 20, 1922.

Application filed March 11, 1921. Serial No. 451,492.

To all whom it may concern:

Be it known that I, ADOLF A. SWANSON, subject of the King of Sweden, residing at Everett, in the county of Middlesex and State of Massachusetts, have invented new and useful Improvements in Stair Structures, of which the following is a specification.

This invention relates to improvements in stair structures and has for its object to provide a cheap, simple, fireproof stair structure of metal and concrete which will be very strong and may be easily and quickly erected.

Another object of the invention is to increase the strength of the stringers by reinforcing the same with concrete which is united with a body of concrete extending across the tread portion of the stairs.

Another object of the invention is to provide a construction which will eliminate the vibrations usually occurring when stairs are constructed of metal.

Still another object of the invention is to provide a novel means for locking the step units in position while being assembled to prevent displacement thereof prior to the application of the concrete and during the interval when the concrete is hardening.

The invention consists in the combination and arrangement of parts set forth in the following specification and particularly pointed out in the claims thereof.

Referring to the drawings:

Figure 1 represents a vertical section through a portion of a stair structure, said section being taken on the line 1—1 of Fig. 2.

Fig. 2 is a vertical section taken on the line 2—2 of Fig. 1.

Like numerals refer to like parts throughout the several views of the drawings.

In the drawings, 5 and 6 represent stringers, 5 constituting a wall stringer and 6 a well stringer. The wall stringer 5 is formed of two parallelly disposed plate 7 and 8 having flanges 9 and 10 respectively extending along their under edges, the flange 9 resting upon the flange 10. The plates 7 and 8 are spaced a suitable distance apart to form

a channel 11 therebetween and said plates are held in correct spaced relation by rivets 12 which secure the flanges 9 and 10 together, and shouldered studs 13 which are riveted to the plates 7 and 8. The flange 10 closes the underside of the channel 11.

The well stringer 6 is formed of two

parallelly disposed plates 14 and 15 having flanges 16 and 17 respectively extending along their under edges, the flange 17 resting upon the flange 16. The plates 14 and 15 are spaced a suitable distance apart to form a channel 18 therebetween and said plates are held in correct spaced relation by rivets 12 which secure the flanges 16 and 17 together and shouldered studs 13 which are riveted to the plates 14 and 15. The flanges 16 and 17 close the underside of the channel 18.

The plates 8 and 15 are each formed with horizontally disposed edges 19 and vertically disposed edges 20. Extending between the stringers 5 and 6 and supported by the plates 8 and 15 of said stringers are a plurality of step units 21 each comprising a horizontally disposed tread support 22 which rests upon the horizontal edges 19 of said plates and a vertically disposed riser portion 23 which rests against the vertical edges 20 of said plates. Opposite end portions of the tread support 22 are bent downwardly at 24 and extend into the channels 11 and 18 in the rear of the studs 13 and a front edge 25 of said portions 24 contacts with the studs 13 which prevent the step units 21 from moving forwardly upon the horizontal edges 19 of the plates 8 and 15. The upper portion of the riser 23 is channel-shaped at 26 thereby forming a seat 27 upon which the front portion of the tread support 22 rests and also forming a flange 28 which constitutes the upper front corner of the finished stair tread. The lower portion of the riser 23 is inclined rearwardly slightly at 29 to form a recess to receive the material constituting a stair tread.

Means are provided for locking the step units 21 in position during the erection of the structure prior to the application of the concrete and during the hardening thereof, said means comprising clips 30 which are mounted upon the studs 13. The clips 30 are preferably constructed of spring steel and are approximately U-shaped in form, having vertically disposed members 31 and 32 through which the studs 13 project, said members being located adjacent to the inner surfaces of the plates forming the stringers 5 and 6. The member 32 is provided with a bent portion 33 at its upper extremity which is adapted to spring over the tread support 22 as illustrated in Figure 2 and thereby prevent said tread support from

lifting from the horizontal edges 19 of the plates 8 and 15.

After the metal portion of the stair structure has been assembled as described, the 5 channels 11 and 18 are filled with concrete, asphalt, cement or any other suitable material 34, after which the tread support 22 is also covered with the same material to the level of the upper surface of the flange 28. 10 The concrete upon hardening reinforces the stringers, strengthens the steel structure and also provides a practical and durable anti-slip tread surface for the steps. Moreover 15 the fact that the concrete comprising the tread portion unites with the concrete within the channels of the stringers makes a more solid structure and prevents the vibrations which usually occur in stairs constructed of metal.

20 While I have illustrated and described a preferred construction of step units and stringers, it will be evident to those skilled in the art that many modifications thereof may be arranged without departing from the 25 spirit of the invention, all of which may be within the scope of the appended claims.

I claim:

1. In a stair structure a pair of stringers each provided with a channel formed therein, a plurality of step units mounted upon 30 said stringers each comprising a tread support and a riser portion and a continuous body of fireproof material located within said channels and extending across said 35 tread support.

2. In a stair structure a pair of stringers each provided with a channel formed therein, a body of concrete located within said channels, a plurality of step units mounted 40 upon said stringers, each comprising a tread support and a riser portion and a body of concrete located upon said tread support and intersecting the concrete of said channels.

45 3. In a stair structure a pair of stringers each comprising a pair of parallel plates forming a channel therebetween, said channels being closed upon the underside thereof, a plurality of step units mounted upon said 50 stringers, each comprising a tread support and a riser portion and a continuous body of fireproof material located within said channels and extending across said tread support.

55 4. In a stair structure a pair of stringers each comprising a pair of parallel plates forming a channel therebetween, said channels being closed upon the underside thereof, a plurality of step units mounted upon 60 said stringers, each comprising a tread support and a riser portion and a continuous body of concrete located within said channels and extending across said tread supports.

65 5. In a stair structure a pair of stringers

each comprising a pair of parallel plates forming a channel therebetween, said channels being closed upon the underside thereof, a plurality of studs located between and separating said plates, a plurality of step 70 units mounted upon said stringers, each comprising a tread support and a riser portion, means mounted upon said studs and engaging said step units to prevent said units from lifting upon said stringers and a body of concrete located within said channels and extending across said tread supports.

6. In a stair structure a pair of stringers each comprising a pair of parallel plates 80 forming a channel therebetween, said channels being closed upon the underside thereof, a plurality of step units mounted upon said stringers, each comprising a tread support and a riser portion, said tread support having flanges at the opposite ends thereof extending into said channels, a plurality of studs separating said plates and preventing a forward movement of said step units upon said stringers, spring clips mounted upon 85 said studs and engaging said step units to prevent said units from lifting upon said stringers and a body of concrete located within said channels and extending across 90 said tread supports.

7. In a stair structure a pair of stringers each comprising a pair of parallel plates forming a channel therebetween, said channels being closed upon the underside thereof, one of the plates of each stringer being provided with a plurality of horizontally disposed edges, a plurality of step units mounted upon said horizontal edges, each comprising a tread support and a riser portion, said tread support having flanges at the opposite ends thereof extending into said channels, a plurality of studs separating the plates of each stringer and preventing forward movement of said step units upon said 100 horizontal edges, spring clips mounted upon said studs and engaging said step units to prevent said units from lifting upon said horizontal edges and a body of concrete located within said channels and extending across said tread supports.

8. In a stair structure a pair of stringers each comprising a pair of parallel plates forming a channel therebetween, said channels being closed upon the underside thereof, one of the plates of each stringer being provided with a plurality of horizontally disposed edges, a plurality of step units mounted upon said horizontal edges, each comprising a tread support and a riser portion, said tread support having flanges at the opposite 110 ends thereof extending into said channels, a plurality of studs separating the plates of each stringer and preventing a forward movement of said step units upon said horizontal edges, U-shaped spring clips mounted 115

upon said studs and embodying therein a pair of resilient members, one of said members having a projection formed thereon engaging said tread support to prevent said units from lifting upon said horizontal edges and a body of concrete located within said channels and extending across said tread supports.

9. In a stair structure a pair of stringers each comprising a pair of parallel plates forming a channel therebetween, said channels being closed upon the underside thereof, one of the plates of each stringer being provided with a plurality of horizontally disposed edges, a plurality of step units mounted upon said horizontal edges, each comprising a tread support and a riser portion, said tread support having flanges at the opposite ends thereof extending into said channels, 20 a plurality of studs separating the plates

of each stringer and preventing a forward movement of said step units upon said horizontal edges, U-shaped spring clips mounted upon said studs and embodying therein a pair of resilient members, one of said members having a projection formed thereon engaging said tread support to prevent said units from lifting upon said horizontal edges and a body of concrete located within said channels and extending across said tread supports, said concrete preventing said spring clips from being disengaged from said step units.

In testimony whereof I have hereunto set my hand in presence of two subscribing witnesses.

ADOLF A. SWANSON.
